UNITED STATES PATENT OFFICE

165,974

DISPLAY STAND

Henry P. Glass, Chicago, Ill., assignor to Grand Rapids Hardware Company, Grand Rapids,
Mich., a corporation of Michigan

Application June 21, 1951, Serial No. 15,625

Term of patent 14 years

(Cl. D80—9)

To all whom it may concern:

Be it known that I, Henry P. Glass, a citizen of the United States, residing at Chicago, in the county of Cook and State of Illinois, have invented a new, original, and ornamental Design for a Display Stand, of which the following is a specification, reference being had to the accompanying drawing, forming part thereof.

The figure is a perspective view of the display stand, showing my new design, the back of the design being plain in appearance.

The dominant features of my design reside in the portions shown in full lines.

I claim:

The ornamental design for a display stand, substantially as shown and described.

HENRY P. GLASS.
